UNITED STATES PATENT OFFICE

HENRY ALISTER THOMPSON, OF YAKIMA, WASHINGTON

LADDER

Application filed February 26, 1929. Serial No. 342,768.

This invention relates to ladders of the type known as step ladders.

A primary object of the invention is to so construct a ladder of this character as to eliminate the use of metal rods employed as supports for the steps and at the same time provide a maximum strength with less weight and greater rigidity throughout.

Another and important object of the invention consists in the step bracing feature employed at the ends of the steps which gives a maximum rigidity to the ladder side.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 represents a front elevation of a ladder constructed in accordance with this invention;

Fig. 2 is an enlarged detail side elevation;

Fig. 3 is a transverse section taken on the line 3—3 of Fig. 2;

Fig. 4 is a horizontal section taken on the line 4—4 of Fig. 2; and

Fig. 5 is a detail perspective view of the rung bracing plate and stirrup.

In the embodiment illustrated a ladder 1 is shown which may be of any desired length and size and which comprises the usual side bars 2 and 3 with transversely arranged longitudinally spaced steps or rungs 4 connecting them and which are designed to support the weight of the user. The side bars are preferably constructed of wood as are also the steps 4. These steps 4 have secured to their lower faces at a point midway the width thereof longitudinally extending ribs 5, it being understood that each step has a single rib. The grain of the wood of the step and its rib is different, said rib being riveted to the step as shown at 6. This construction while relatively light in comparison with the iron or steel rods used adds approximately 40% to the strength of the step.

At each end of each step 4 is a U-bolt 7 which extends through the rib 5 and the adjacent side bar, one of the rivets 6 passing

through the bolt at its closed end as shown clearly in Fig. 4. The free ends of the bolt 5 which project beyond the side bar of the ladder are provided with nuts 8 which when screwed up tighten the parts and hold them rigidly and securely together. A plate or washer 9 is arranged on the outer face of the side bar of the ladder and through which the legs of the bolt extend as shown clearly in Fig. 4.

Arranged between each end of the rungs or steps 4 and the adjacent inner face of the side bar of the ladder is a bracing plate or stirrup 10 having an inwardly extending lateral flange 11 at the upper portion thereof which is shaped to fit over the step 4 at its end while the U-bolt passes through apertures 12 therein and cooperates with the plate to securely hold the step in engagement with the ladder side bar. The plate 10 is also provided with a plurality of out struck prongs 13, two being here shown, which are designed to be imbedded in the side bar as shown in Fig. 4 to assist in holding the parts assembled. As shown in Fig. 2 an inclined washer 9a is disposed between the nuts 8 and the washer 9 to provide for the tightening up of the U-bolt against the inclined face of the side bar it being of course understood that when the side bars are parallel as shown in Fig. 1 these washers 9a will not be necessary.

A reinforcing or wear plate 14 is shown in Fig. 2 arranged below the rib 5 and through which the rivets 6 are designed to pass.

It will be obvious that use of the U-bolts at both ends of each step or rungs insures a strong grip and support and provides means which are easily tightened to hold the parts rigidly together. The gist of the invention resides in the self-bracing feature insured by about two inches of the step end which renders the ladder sides rigid and strong.

In Fig. 1 a ladder is shown in which the side bars are made parallel with each other while in Fig. 2 the side bar there shown is inclined, ladders being frequently constructed with their side bars converging towards the upper end.

Without further description it is thought

that the features and advantages of the invention will be readily apparent to those skilled in the art, and it will, of course, be understood that changes in the form, proportion and minor details of construction 5 may be resorted to, without departing from the spirit of the invention or its scope as claimed.

I claim:

1. A ladder comprising side bars with steps arranged between them, each of said steps having a rib extending longitudinally of its lower face and riveted to the step, the grain of the wood of the step and the rib extending in different directions, U-bolts 15 extending through said ribs and side bars for connecting the steps to the side bars, and means for securing said bolts in position.

2. A ladder comprising side bars with steps 20 arranged between them, each of said steps having a rib extending longitudinally of its lower face and riveted to the step, the grain of the wood of the step and the rib extending in different directions, U-bolts extending 25 through said rib and side bars for connecting the step to the side bars and bracing plates arranged between the ends of the step and the side bars, said plates having means 30 for connecting them with the steps and with the side bars and means for securing said U-bolts in position.

3. A ladder comprising side bars with steps arranged between them, each of said steps 35 having a rib extending longitudinally of its lower face and riveted to the step, the grain of the wood of the step and the rib extending in different directions, U-bolts extending through said ribs and sides for connecting the steps to the side bars and nuts for 40 securing said bolts in position, bracing plates mounted between the ends of the steps and the adjacent side bars of the ladder, each plate having an inturned flange to fit around the end of the step and outturned spurs to 45 engage the side bar, the U-bolts passing through said plate to assist in holding the parts assembled.

4. A ladder including side bars with steps arranged between them, a rib extending 50 longitudinally of the lower face of each step, said ribs being riveted to the step, U-bolts extending transversely through the ends of the ribs and behind the end rivets, with the legs of the bolts extending parallel with and 55 engaging opposite side faces of the rib, said bolt legs passing through the adjacent side bar of the ladder and nuts for securing said bolts in position and for tightening them up to hold the parts rigidly assembled.

5. A ladder including side bars with steps 60 arranged between them, a rib extending longitudinally of the lower face of each step, said rib being riveted to the step, U-bolts extending transversely through the ends of 65 the ribs with the legs of the bolt extending

parallel with and engaging opposite side faces of the rib, said bolt legs passing through the adjacent side bar of the ladder, and nuts for securing said bolts in position and for tightening them up to hold the parts rigidly 70 assembled, each step having a plate arranged over the ends thereof and located between said end and the adjacent face of the ladder side bar, said plate having step encircling means and means for engagement with the ladder side bar, said plate having apertures through which the U-bolts extend. 75

6. A ladder comprising side bars with steps arranged between them, each of said steps having a rib extending longitudinally of its lower face and riveted to the step, U-bolts 80 extending through said ribs and sides for connecting the steps to the side bars and nuts for securing said U-bolts in position, and bracing plates mounted between the ends of the steps and the adjacent side bars of the ladder, each plate having an inwardly extending flange encircling the top and side 85 portions of the step and having a pair of shoulders upon the lower side defining a seat 90 for the end portion of each step, said shoulders stopping short of the medial portion of said plates and said plates having an aperture formed adjacent each shoulder for the passage therethrough of the legs of the U-bolts. 95

Signed at Yakima, in the county of Yakima and State of Washington, this 21st day of February, A. D. 1929.
